US00D972842S

(12) United States Design Patent (10) Patent No.: US D972,842 S
(45) Date of Patent: * Dec. 20, 2022

(54) POUCH

(71) Applicant: Kimberly Cundick, Saint George, UT (US)

(72) Inventor: Kimberly Cundick, Saint George, UT (US)

() Term: 15 Years

(21) Appl. No.: 29/741,088

(22) Filed: Jul. 9, 2020

(51) LOC (13) Cl. 03-01

(52) U.S. Cl.

USPC D3/301; D3/289

(58) Field of Classification Search

USPC D3/274, 276, 285, 289, 290, 306, 313, D3/203.1, 203.6, 205, 226, 230, 232, 242, D3/245, 246, 267, 268, 273, 275, 283, D3/284, 286, 287, 288, 294, 295, 301, D3/303, 900, 901, 903, 201, 215, 218, D3/221, 222, 228, 240, 251, 270, 271.9, D3/296, 247, 34, 74, 78, 298, 75, 262, D3/299, 208, 203.2, 203.3, 203.4, 203.5, D3/203.7, 203.8, 204, 206-212, 254-258; D7/607, 609; D27/172, 183, 186, 190, D27/191; D28/73, 76, 99; D9/420, 709; D19/26, 57, 62, 113, 157; D14/250, 440, D14/447; D6/582-583, 601, 616; D29/119
